UNITED STATES PATENT OFFICE.

EDSON F. GALLAUDET, OF NORWICH, CONNECTICUT.

SYSTEM OF AEROPLANE CONTROL.

1,074,257.

Specification of Letters Patent. Patented Sept. 30, 1913.

Application filed May 9, 1910. Serial No. 560,192.

To all whom it may concern:

Be it known that I, EDSON F. GALLAUDET, a citizen of the United States, and resident of the city of Norwich, in the county of New London and State of Connecticut, have invented a certain new and useful System of Aeroplane Control, of which the following is a specification.

The present invention relates to a system of aeroplane control which is applicable both to monoplanes and multiplanes, whether gliders or motor driven; and it has for its object to provide improved means and methods for maintaining the lateral balance of flying-machines of the aeroplane type.

When a wing or sustaining plane of a flying-machine, which is given a positive angle of incidence thereby making its under side a compression surface, is tilted laterally the reaction thereof, acting in a line at an angle to the perpendicular, may be resolved into its vertical or lifting component and a horizontal component which tends to force 25 to one side the part to which the wing is attached. Consequently, if such a plane is mounted above or below the longitudinal axis of the machine the vertical component of its reaction, when the machine tilts over 30 to one side or the other, will serve to lift or sustain the machine while the horizontal component thereof will tend to resist or overcome the tilting movement by forcing the top or bottom of the machine, as the 35 case may be, toward that side to which the plane is inclined; and, by causing two sustaining planes mounted respectively above and below the longitudinal axis of the machine to assume suitable differential trans- 40 verse angular positions, a couple will be produced around the longitudinal axis of the machine by the horizontal components of the reactions of the planes which may be utilized to tilt the machine over to one side 45 or the other, as desired, or to restore it to a horizontal position when tilted.

My invention therefore comprises, in its broadest aspect, mounting one or more of the main or auxiliary or supplemental sus- 50 taining planes of an aeroplane so that it or they may be tilted laterally to either side of the machine and utilizing the horizontal component of the reaction or reactions thereof, when tilted, for controlling the ma-

chine and maintaining it in lateral balance. 55 In its preferred form, a single auxiliary plane is suitably mounted centrally above and a second plane is mounted centrally below the main fixed wings of a monoplane or multiplane machine and the lateral balance of the machine is controlled by causing both upper and lower auxiliary planes to tilt differentially to one side or the other and to such degree as may be required for the purpose. 60

The invention also comprises the novel features and combinations of parts herein- 65 after described and more specifically pointed out in the claims.

The invention is adapted for use inde- 70 pendently of or in connection with the system of lateral control by means of balancing rudders which constitute the subject-matter of an earlier application.

Means embodying my invention and suitable for carrying into practical effect my new method of maintaining lateral control of an aeroplane are illustrated in the accompanying drawings, in which, similar reference numerals being used throughout to indicate like parts, Figure 1 is a perspective view showing in outline the principal parts of a monoplane gliding machine equipped with upper and lower auxiliary planes which are adapted to be tilted to one side 85 or the other, in opposite directions, to control the lateral balance of the machine; Fig. 2, a diagram showing the direction of the reactions thereof when the main and auxiliary planes are all horizontal and parallel; 90 Figs. 3 and 4, diagrams showing the positions of the auxiliary planes when tilted to restore the aeroplane to horizontal position from a tilt to port and from a tilt to starboard, respectively, and indicating the direction of the reactions of such planes and of the component forces thereof; Fig. 5, a perspective view showing in outline the same monoplane gliding machine shown in Fig. 1 equipped with upper and lower aux- 95 illary planes mounted and operating in a somewhat different manner; Fig. 6, a dia- 100 gram showing the positions of the auxiliary planes when tilted to restore the aeroplane to horizontal position from a tilt to port and indicating the direction of the reactions of the planes and also of the component forces of such reactions. 105

Referring first to Fig. 1 of the drawings, the aeroplane there illustrated comprises the main wings 1, which are rigidly mounted a little forward of the longitudinal center of the main spar 2, and the forward gradient 3, rear gradient 4, forward double rudder 5 6, and rear double rudder 7 8, which are mounted to rotate, the gradients on transverse horizontal axes and the rudders, either 10 for steering only or for both balancing and steering, on vertical axes, and which are actuated by any suitable controlling mechanism. The upper auxiliary plane 9, pivoted at its longitudinal center between the upper ends of central vertical posts 10 and 11, braced by guy-wires 15, by means of horizontal fore and aft pins 12 and 13 journaled in bearings formed in the top heads of the vertical posts, is given an angle of incidence substantially the same as that of the rigid main wings and is adapted to be rocked transversely about the axial line formed by the horizontal pins. The lower auxiliary plane 16 is similarly mounted between the lower ends of the central vertical posts 17 and 18, braced by guy-wires 21, by means of horizontal fore and aft pins 19 and 20 bearing in the bottom heads of the vertical posts so as to have substantially 20 the same angle of incidence as the rigid main wings and rock transversely about the axial line formed by its pivotal bearings. The upper auxiliary plane 9 is operatively connected with any suitable control mechanism, here shown as comprising a sheave 25 mounted to rotate with the shaft 26 by the transverse swinging, either automatically by gravity or manually by the operator, of the steering shaft 27 and steering wheel 28, by 30 the cable 22 the two ends of which lead directly from opposite sides of the sheave 25 to and are secured in eyes 23 and 24, respectively, suitably mounted at the front edge of the plane on correspondingly opposite sides of its pivotal axis and at equal distance therefrom. The lower auxiliary plane 16 is similarly connected with the sheave 25 of the control mechanism by the crossed cable 29 the ends of which lead from the two 40 opposite sides of the sheave to and are secured in reversely opposite eyes 30 and 31, respectively, suitably mounted on the front edge of the plane on either side of its longitudinal center. 50 It is evident that, when the steering wheel and shaft swing or are swung transversely to one side or the other, the sheave will be rotated and through the cable 22 will give a similar angular movement to the upper auxiliary plane and through the cable 29 will give an opposite angular movement to the lower auxiliary plane, thus producing a tilting or righting couple about the longitudinal axis of the machine by reason of the 60 positively acting horizontal components of the

reactions of these two planes. The lifting and balancing action of the auxiliary planes is clearly shown in Figs. 2, 3, and 4. When the fixed main wings are horizontal and the auxiliary planes are parallel therewith, the reactions of all three planes are in the same vertical line, indicated by the arrow 32 in Fig. 2, and the auxiliary planes exert lifting forces only. If the aeroplane becomes tilted to port, the upper auxiliary plane is tilted to starboard and the lower auxiliary plane to port, as shown in Fig. 3, and in these new positions the reactions of the two planes, indicated by the arrows 33 and 36 respectively, may be resolved into their component forces, one acting directly in line with the reaction of the main wings as indicated by the dotted arrows 34 and 37 respectively, and the other, indicated by the dotted arrows 35 and 38 respectively, acting at right angles thereto and tending to restore the aeroplane to its normal horizontal position. If on the other hand the aeroplane should be tilted to starboard, the upper auxiliary plane is tilted to port and the lower auxiliary plane to starboard, as shown in Fig. 4, and in these new positions the reactions of the planes, indicated by the arrows 39 and 42 respectively, may be resolved into component forces acting one directly in line with the reaction of the main wings as indicated respectively by the dotted arrows 40 and 43 and the other indicated by the dotted arrows 41 and 44 respectively, at right angles thereto and tending to restore the aeroplane to its normal horizontal position.

In the modified form illustrated in Fig. 5, the auxiliary plane 45 is mounted above the fixed main wings 1 by means of the four pivoted link-bars 46, 47, 52, and 53, the two former being pivoted at their lower ends to the upper side of the main starboard wing by elbow-heads journaled respectively in bearings 48 and 49 and at their upper ends by pins 50 and 51 secured respectively to the front and rear edges of the auxiliary plane on one side of its longitudinal center and bearing in the top heads of the link-bars, and the two latter by bottom elbow-heads journaled in bearings 54 and 55 on the upper side of the main port wing and by pins 56 and 57 secured respectively to the front and rear edges of the auxiliary plane on the other side of its longitudinal center and bearing in the top heads of said link-bars. The lower auxiliary plane 58 is similarly mounted below the main wings by means of the pivoted link-bars 59, 60, 63, and 64, the two former being pivoted by top elbow-heads journaled in bearings (not shown) on the under side of the main starboard wing and by pins 61 and 62 secured respectively to the front and rear edges of the auxiliary plane on one side of its longitudinal center and bearing in the bottom heads of the link-

bars, and the two latter by top elbow-heads journaled in bearings (not shown) on the under side of the main port wing and by pins 65 and 66 secured respectively to the front and rear edges of the auxiliary plane on the other side of its longitudinal center and bearing in the bottom heads of said link-bars. The cable 71 passes around the sheave 25 of the central controlling mechanism and from the two sides thereof its ends lead directly to the corresponding ends of the upper auxiliary plane to which they are respectively secured by pins 72. The crossed cable 73 also passes around the sheave 25 and from opposite sides thereof its ends cross and lead to the reversely opposite ends of the lower auxiliary plane to which they are respectively secured by pins 74.

20 It is evident that the rotation of the sheave 25, whenever the steering wheel and shaft swing or are swung transversely to one side or the other of the aeroplane, will through the cables 71 and 73 give a similar angular movement to the upper and an opposite angular movement to the lower auxiliary plane and, simultaneously therewith, cause both planes to move bodily over toward the side of the aeroplane toward 25 which the steering wheel and shaft have been swung, thereby producing a tilting or righting couple which is supplemented and thereby made more effective by the vertical or lifting component of the reactions of the two auxiliary planes, which, owing to the lateral displacement of these planes, are now acting to one side of its longitudinal axis to raise the lower side of the machine. When, for example, the aeroplane is tilted 30 over to port so as to give the main wings the position shown in Fig. 6, with a reaction in the line indicated by the arrow 75, the upper and lower auxiliary planes will be moved to the positions there shown and, in 35 such new positions, their reactions, respectively indicated by the arrows 76 and 79, may be resolved into component forces, the one, indicated by the dotted arrows 77 and 80 respectively, acting in lines parallel with 40 but eccentric to the line of reaction of the main wings and the other acting at right angles thereto as indicated respectively by the dotted arrows 78 and 81.

While I have specifically described my 45 new system of aeroplane control only with reference to the particular embodiments thereof which are illustrated in the drawings, it will be understood that its details may be variously modified without departing 50 from the spirit or sacrificing the advantages of the invention. For example, a single auxiliary movable plane mounted either above or below the main wings may be used; the movable planes may be enlarged 55 and constitute the main or sole lifting and

sustaining surfaces of the machine; the means by which the planes are mounted to rock or rock and move transversely may be modified in obvious ways; and any suitable controlling mechanism may be employed to 70 actuate the movable planes. Such other modifications may be made as fall within the scope of the appended claims.

What I claim as new, and desire to secure by Letters Patent, is—

1. The combination, in an aeroplane, of a fixed sustaining plane, a movably mounted sustaining plane, and means for simultaneously effecting both a lateral displacement and a transverse angular movement of 80 said movable with respect to said fixed plane.

2. The combination, in an aeroplane, of sustaining planes suitably mounted centrally above and below the longitudinal axis of the 85 aeroplane and means for simultaneously effecting a similar lateral displacement and an opposite transverse angular movement of said planes.

3. The combination, in an aeroplane, of 90 fixed main wings, auxiliary sustaining planes mounted centrally above and below said main wings to have lateral and transverse angular movement, and a control mechanism adapted to simultaneously effect 95 a similar lateral displacement and an opposite transverse angular movement of said auxiliary planes.

4. The combination, in an aeroplane, of 100 fixed main wings, auxiliary sustaining planes mounted centrally above and below said main wings, and means for simultaneously effecting a similar lateral displacement of said auxiliary planes.

5. The combination, in an aeroplane, of 105 fixed main wings, an auxiliary sustaining plane mounted centrally above said main wings on pivoted link-bars having transverse angular movement and different angular positions on the opposite sides of the 110 longitudinal center of the aeroplane, and means for effecting a transverse angular movement of said link-bars.

6. The combination, in an aeroplane, of a fixed main sustaining plane, auxiliary planes mounted centrally above and below said main plane on pivoted link-bars having transverse angular movement and different angular positions on opposite sides of the longitudinal center of the aeroplane, and 120 means for simultaneously effecting similar transverse angular movement of the link-bars upon which said upper and lower auxiliary planes are respectively mounted.

7. The combination, in an aeroplane, of a 125 fixed main sustaining plane, auxiliary sustaining planes mounted centrally above and below said main plane, link-bars having transverse angular movement and different angular positions on opposite sides of the 130

longitudinal center of the aeroplane, a sheave, cables operatively connecting the opposite sides of said sheave with the corresponding opposite ends of the upper auxiliary plane and with the reversely opposite ends of the lower auxiliary plane, respectively, and means for rotating said sheave.

In witness whereof I have hereunto signed my name in the presence of two witnesses:

EDSON F. GALLAUDET.
